HANDLE GRIPPING SLEEVE FOR A TENNIS RACKET OR THE LIKE

James R. Cope, 10500 Cherokee Lane,
Leawood, Kans. 66108

Filed Sept. 4, 1974, Ser. No. 503,174

Term of patent 14 years

Int. Cl. D21—02

U.S. Cl. D34—5 ST

Fig. 1.

Fig. 2.

Fig. 3.

Fig. 4.

Fig. 5.

Fig. 6.

FIG. 1 is an end elevational view of the butt end of the hand gripping sleeve for a tennis racket or the like;

FIG. 2 is an end elevational view of the open end of the sleeve;

FIG. 3 is a top plan view of the sleeve;

FIG. 4 is a side elevational view showing one side of the sleeve;

FIG. 5 is a bottom plan view; and

FIG. 6 is a side elevational view showing the opposite side of the handle gripping sleeve for a tennis racket or the like.

I claim:

The ornamental design for a handle gripping sleeve for a tennis racket or the like, as shown.
